LAYOUT FOR RESTAURANTS

Filed Feb. 3, 1930

Charles G. Hall

INVENTOR

Frank B. Lillie
ATTORNEY

UNITED STATES PATENT OFFICE

CHARLES G. HALL, OF BOISE, IDAHO, ASSIGNOR TO AUTOMATIC FOOD MACHINERY CORPORATION, OF BOISE, IDAHO

LAYOUT FOR RESTAURANTS

Application filed February 3, 1930. Serial No. 425,702.

My invention relates to restaurant layouts and consists primarily of a kitchen and an endless conveyor running from the kitchen longitudinally of the dining compartment of the restaurant. Chairs are disposed adjacent either side of the endless conveyor. Booths having tables disposed therein are disposed adjacent one side of the dining compartment into which the patrons may dine; the food 10 being delivered or transferred from the conveyor to the booths by waiters.

Turn-stiles are provided for the entry of the patrons into the restaurant. Provision is made for each of the patrons being required 15 to pass a cashier's desk as they leave the eating establishment. A central office is provided on an elevated platform in order that the entire operation in the kitchen and in the dining room may be viewed from one central 20 location.

The primary object of my invention is to conserve space in a highly congested, high rent district.

In large centers of population rent is predicated upon the number of front feet of area that is utilized. Through the use of my new and improved arrangement a minimum of front footage is required to satisfy and care for a relatively large number of patrons.

Through the use of my arrangement the amount of help required for the serving of the patrons is also reduced to a minimum.

A further object of my invention consists in providing means whereby the time required 35 for serving the patron is reduced to a minimum.

A still further object of my invention consists in providing an arrangement, through the use of which, the proprietor, or owner of 40 the establishment may view the entire area occupied from one central working office.

A still further object of my invention consists in providing means for serving the patrons from the kitchen or work room and 45 means for delivery of the soiled dishes and linen to the central work room for reconditioning.

A still further object of my arrangement 50 consists in providing a relatively narrow eating and cooking establishment and yet allow

two entrances and two exits from the front of the establishment.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a plain view of the restaurant and kitchen.

Fig. 2 is a fragmentary, sectional, side view 65 of the office portion of the restaurant, the same being taken on line 2—2 of Fig. 1, looking in the direction indicated.

Like reference characters refer to like parts throughout the several views.

1 is the eating portion of the restaurant and 70 2 is the kitchen portion of the restaurant. Entrance doors 3 and 4 are provided for the admission and exit of the patrons of the establishment. Turn-stiles 5 and 6 are provided through which the patrons must pass from one direction only. Entry and exit may also be made through the passageways 7 and 8, but under normal conditions the passageways are 75 for exit only. When the patron passes through the passageways 7 and 8 he must come directly in front of the cashier's desk 80

9. The cashier's desk has a plurality of table tops 10 and 11 upon which change may be made and the charge slips deposited. The 85 cashier is positioned within the recess 12 so that he may have easy access to the cash register disposed upon the cashier's desk between the table tops. A plurality of dining tables 13 are provided along one side of the restaurant. 90 The tables may be placed within booths 14 or placed unprotected directly within the dining room. A conveyor 15 runs longitudinally of the eating room and the kitchen. The eating room and kitchen are divided by a partition 24.

The food that is to be conveyed to the dining room is deposited upon the conveyor 15 and may be picked directly therefrom by the patrons sitting in chairs or stools 16 disposed 100

on each side of the conveyor. The food may either be taken from the conveyor by the patrons sitting at the table or within the booths, or it may be transferred from the conveyor 5 to the tables or booths, by waiters. The soiled dishes and linen are carried by conveyor belts 17 that are disposed at either side of the conveyor 15. The soiled dishes and linen are delivered from the belt conveyors upon the 10 ceiling head 18 from where they are taken to be reconditioned and reassembled for use. Kitchen doors 25 and 26 are provided for ingress and egress of the assistants to and from the kitchen. The office portion has an ele- 15 vated platform 19 disposed therein upon which the manager may work. Windows 20 and 21 are provided within the respective ends of the office and a side window 22 is pro- 20 vided within the side thereof so that the manager may observe the complete operation of the institution from one central location, access being had to the raised platform by any suitable means as by a stairway 23. The office is situated on the same side as the tables or 25 booths.

While the layout herein shown and described is admirably adapted to fulfill the objects primarily stated, it is to be understood that it is not intended to confine the invention 30 to the one form of embodiment herein shown and described, as it is susceptible of embodiment in various forms, all coming within the scope of the claims which follow:

What I claim is:

- 35 1. In a restaurant of the class described, the combination of an eating compartment and a kitchen compartment separated by a partition, an endless conveyor running longitudinally of each compartment and through 40 the partition, a reconditioning head disposed at one end of the conveyor and a pay station disposed at the oppositely disposed end of the conveyor, entrance ways disposed at the street end of the eating compartment, and 45 exit passageways disposed at the entrance end, said exit passageways leading past the pay station and tables and booths disposed within the eating compartment and in spaced relation with the endless conveyor.
- 50 2. In a restaurant of the class described, the combination of an eating compartment and a kitchen compartment separated by a partition, an endless conveyor running longitudinally of each compartment and through 55 the partition, conveyor belts longitudinally disposed on each side of the endless conveyor and running in the opposite direction, seats arranged adjacent each side of the group of conveyors within the eating compartment, a 60 reconditioning head disposed at the kitchen end of the conveyors, a pay station disposed at the oppositely disposed end of the conveyors, ingress and egress passageways disposed at the street end of the eating compartment, 65 ingress and egress passageways disposed

through the partition on each side of the conveyors, a plurality of booths disposed in spaced relationship with the conveyors, and an elevated look-out station disposed at the location of the partition on the same side as 70 the booths.
